UNITED STATES PATENT OFFICE.

GEORGE CALVERT, OF LONDON, ENGLAND.

APPARATUS FOR MIXING GASES AND LIQUIDS.

1,123,092.

Specification of Letters Patent. Patented Dec. 29, 1914.

Application filed February 18, 1914. Serial No. 819,523.

To all whom it may concern:

Be it known that I, GEORGE CALVERT, subject of the King of Great Britain, residing at London, England, have invented certain new and useful Improvements in Apparatus for Mixing Gases and Liquids, of which the following is a specification.

This invention relates to apparatus for use in the hydrogenization of oils and similar processes where a charge of liquid substance and gas or gases are mixed in the hot state under pressure, and the object of the present invention is to secure a more perfect commingling of the substances under maintenance of the pressure and temperature and with exclusion of foreign matters such as air, and to minimize leakage.

It is well known that considerable loss of hydrogen occurs in the hydrogenization of oils and that with the high temperatures and pressures used it has hitherto been extremely difficult to prevent leakage and to maintain the desired high pressure which I have found necessary to produce a good result. The temperature at which the high mixture occurs also entails difficulties rendering it impracticable to bring the motor directly into the mixing chamber.

The present invention seeks to overcome those difficulties associated with mixing of more or less attenuated fluids at high pressures and temperatures.

In the hydrogenization of oils and the like, according to the present invention, I employ mixing or commingling means capable of being operated within the inclosure containing the charge to be dealt with, and which commingling means is operated by a motor also within the aforesaid inclosure, whereby the passage of any moving parts through the walls of the inclosure is avoided.

The invention also comprises the particular combination and arrangement of parts as hereinafter described.

The invention will be more readily understood from the following description of some convenient forms illustrated somewhat schematically which are suitable for use in the commingling of hydrogen with oils in the hydrogenization of such oils, especially in the known manner where gas mingled with oil or oil vapors is brought into contact with catalytic material. The devices shown may however also be used for analogous purposes where a charge of material is to

be treated for a protracted period under heat and pressure.

In the drawings:

Figure 1 is a sectional elevation of one convenient form employing a rotary stirrer as the commingling means. Figs. 2 and 3 are sectional elevations of two convenient forms in which the commingling means comprise a circulating pump adapted to circulate the gas. Figs. 4 and 5 are sectional elevations illustrating other forms of apparatus.

According to the form shown in Fig. 1, a gas tight inclosure comprises a commingling chamber *a*, a motor chamber *e* and a pipe *d* connecting the two. The liquid to be treated such as oil, is placed in the commingling chamber *a* which if required may be heated in any suitable manner, as for instance, by means of a superheated steam jacket *B*. The commingling means is in the form of stirrer blades *c* mounted on a shaft *b* which passes through the pipe *d* and is driven by a motor *f* which is preferably an electric motor and is located within the motor chamber *e*. The electric motor *f* in the case of the hydrogenization of oils is preferably a motor of the induction type so as to avoid sparking. The gas which is to be commingled with the oil is supplied to the gas tight inclosure by a pipe *g* which for instance may be connected to the motor chamber *e*, the gas passing from said chamber through the pipe *d* into the commingling chamber *a*. The pressure in the commingling chamber *a* may be read from a pressure gage *h*. In the hydrogenization of oils I find this pressure is preferably fairly high and hence the great difficulty associated with the prevention of leakage if the stirring mechanism for the shaft *b* passes through a stuffing gland. In the apparatus described there are no packing glands for any moving parts passing through the walls of the gas tight inclosure and consequently even hydrogen cannot leak from the interior of the vessel. In spite of the high pressure and owing to the high speeds attainable a more efficient mixing occurs than with a spraying apparatus.

In order to prevent vapor rising to the motor chamber *e* and to maintain this chamber fairly cool, a cooling jacket *i* through which water circulates by the pipes *j* may be arranged on the connecting pipe *d*. The finished product may be removed from the

commingling chamber a by a pipe k . It will be understood that the electric current will be supplied to the electric motor f through insulating plugs C which are rendered pressure tight in any well known manner such as that used for example in the construction of sparking plugs for internal combustion engines.

- 5 In the form just described with reference to Fig. 1, the motor is inclosed in a chamber which is at the same pressure as that of the commingling chamber a . In the form shown in Fig. 2 the electric motor f' on the motor chamber e' is under the same pressure as that of the hydrogen or other gas which is introduced at the inlet pipe g . The gas in this instance is circulated by a pump m which draws in gas through the pipe d' and liquid through the pipe n while the gas and liquid which are thoroughly mixed in the pump m pass in the commingled state by the pipe o into the chamber a' in which chamber they may be heated if required, for instance by superheated steam circulated 25 through a jacket B .

The discharge p from the pipe o may lead into the top of the chamber a' as shown in Fig. 2, or as indicated at p' Fig. 3, the discharge may be led into the lower part of 30 the heating chamber. In Fig. 3 the pump m' only pumps the gas and the motor f'' is inclosed in its chamber e which is at the same pressure as that in the heating chamber a'' . The gas pipe n' conveniently terminates in a perforated discharge cone p' .

According to the form shown in Fig. 4 substantially the same construction is used as that illustrated in Fig. 1. The gas in this instance however, is forced under pressure 40 into the same part of the commingling chamber a^3 by a self contained pump fed from a gas holder; for instance the gas may be forced by a pump q driven by suitable worm gearing, from the shaft of the electric motor f^3 . With the pump q arranged as shown within the main gas-tight inclosure, although for convenience its cylinder q' forms an extension of the motor chamber e^2 , no leakage to the atmosphere is possible. The pump q comprises a piston q^2 reciprocated by the worm wheel r' through a connecting rod r^2 , the worm wheel r' being driven by a worm r on the shaft b of the electric motor. The piston q^2 is provided 50 with a check valve q^3 while the second check valve q^4 is provided in the bottom of the cylinder q' above a pipe x' connected to a gas holder v . When sufficient pressure is produced in the chamber a^3 the supply of 60 gas may be cut off by a valve s on the pipe x' which may be controlled automatically, as for instance by a pressure motor or diaphragm t connected to the chamber e^2 by a pipe u . Thus although the pump may still 65 continue to run, the pressure will be re-

tained within the required limits which for example may be 250 lbs. per square inch. The gas is stored in a gas holder v which after the commingling operation has been completed the pressure in the chamber a^3 is relieved by opening a valve w in a return pipe x leading to the gas holder v so that at the end of each treatment and before the treated substance is discharged, the surplus gas in the chamber a^3 is not wasted but is 70 returned to the gas holder v .

When starting the operation the valve w is closed and the pressure pump q then operates to produce the pressure required.

In a further form of the apparatus shown 80 in Fig. 5 the commingling chamber a^4 of non-magnetic material is arranged between the poles of a rotary or oscillatory electromagnet y energized by a coil or coils z supplied with electric current from any suitable 85 source through the medium of brushes z^3 and slip rings z' mounted on the shaft z^2 which carries the electromagnet and to which shaft the desired rotary or oscillatory movement is imparted in any manner 90 common in the art of electrical engineering. Within the mixing or commingling chamber a^4 stirrer blades c^4 mounted on a freely rotatable shaft b^4 are arranged. The stirrer blades c^4 are provided at their tips with suitable 95 pole pieces c^5 of magnetic material.

It will be understood from the above that on rotary or oscillatory movement of the electromagnet the stirrer blades are caused by magnetic action to follow the movement 100 of the electromagnet. The mixing or commingling chamber a^4 is constructed of material which is a conductor of electricity so that owing to the fact that it is arranged in the path of a moving magnetic field, eddy 105 currents will be induced in the walls of the mixing or commingling chamber serving to augment the heating of the contents thereof.

I claim:

1. For use in the hydrogenization of oils 110 and analogous processes where a gas and a liquid charge are mixed in the hot state under pressure, a chamber for containing the liquid and gas to be mixed, means for heating said chamber, means for commingling the gas and liquid in the aforesaid chamber, a motor for operating said commingling means, said motor being remote from said chamber and having a casing and means for connecting said chamber and 115 said motor casing to form therewith a common gas-tight inclosure, whereby the passage of moving parts through the walls of the inclosure are avoided, substantially as and for the purpose hereinbefore set forth. 120
2. For use in the hydrogenization of oils and analogous processes where a gas and a liquid charge are mixed in the hot state under pressure, commingling means, an electric motor for operating said commingling 125 130

- means and a gas-tight inclosure common to said commingling means and motor, substantially as and for the purpose hereinbefore set forth.
5. 3. For use in the hydrogenization of oils and analogous processes where a gas and a liquid charge are mixed in the hot state under pressure, commingling means, an electric motor for operating said commingling means and having a driving shaft connecting said means and motor, a gas-tight inclosure common to said commingling means and motor, said inclosure comprising a commingling chamber in which the aforesaid 10 commingling means is located, a motor chamber in which the said electric motor is located, and a pipe connecting the said commingling chamber and motor chamber and inclosing the aforesaid driving shaft, substantially as and for the purpose hereinbefore 15 set forth.
4. For use in the hydrogenization of oils and analogous processes where a gas and a liquid charge are mixed in the hot state under pressure, commingling means, an electric motor for operating said commingling means and having a driving shaft connecting said means and motor, a gas-tight inclosure common to said commingling means 20 and motor, said inclosure comprising a commingling chamber in which the aforesaid commingling means is located, a motor chamber in which the said electric motor is located, and a pipe connecting the said commingling chamber and motor chamber and inclosing the aforesaid driving shaft, said pipe having a cooling jacket, substantially as and for the purpose hereinbefore 25 set forth.
5. For use in the hydrogenization of oils and analogous processes where a gas and a liquid charge are mixed in the hot state under pressure, a gas-tight inclosure comprising a commingling chamber, a motor chamber and a pipe connection between said commingling chamber and motor chamber, commingling means within said inclosure and an electric motor inclosed in said motor chamber for operating said commingling 30 means, substantially as and for the purpose hereinbefore set forth.
6. For use in the hydrogenization of oils and analogous processes where a gas and a liquid charge are mixed in the hot state under pressure, a gas-tight inclosure comprising a commingling chamber for the oils to be treated, a motor chamber and a pipe connection between said commingling chamber and motor chamber, a pipe for supplying gas to said commingling chamber, means 35 for commingling the gas and oil in said commingling chamber, and an electric motor within the aforesaid motor chamber for operating said commingling means, substantially as and for the purpose hereinbefore 40 set forth.
7. For use in the hydrogenization of oils and analogous processes where a gas and a liquid charge are mixed in the hot state under pressure, a gas-tight inclosure for containing oil and gas, means for commingling said oil and gas, said commingling means being located within said inclosure, and an electric motor, also located within said inclosure, for operating said commingling 45 means.
8. For use in the hydrogenization of oils and analogous processes where a gas and a liquid charge are mixed in the hot state under pressure, a gas-tight inclosure for containing oil and gas, means for commingling said oil and gas, said commingling means being located within said inclosure, an electric motor also located within said inclosure for operating said commingling means, 50 a gas pump operated by said motor, a gas holder, and connections from said pump and gas holder to said inclosure, substantially as and for the purpose hereinbefore 55 set forth.
- In testimony whereof I have signed my name to this specification in the presence of two subscribing witnesses.
